GEORGE H. CHESTER, OF RICHMOND HEIGHTS, MISSOURI

SELF LOCKING HINGE

Application filed September 26, 1929. Serial No. 395,214.

This invention relates to new and useful improvements in hinges, the objects of the invention being the provision of a hinge which is adapted to limit the opening movement of the closure member.

Further objects of the invention are to provide a hinge wherein the pintle member is movable axially in correlation with the opening movement of the closure member, such 10 axial movement of said pintle member being restricted to limit the opening movement of the closure member.

Other objects of the invention are to provide a self-locking hinge wherein the pintle member is movable axially to clamp the movable leaf member between the stationary leaf member and an enlargement on said pintle, thereby limiting the swinging movement of the closure member in accordance with the 20 extent of the axial movement of said pintle member.

Still other objects of the invention are to provide a hinge, one member of which is provided with a threaded bore, the pintle member of said hinge being screw-seated in said bore, said pintle member being partially rotatable in conjunction with the closure member, thereby receiving movement in axial direction by virtue of the screw-threaded engagement and bringing an enlargement on 25 said pintle member in pressure contact with the movable hinge member, thereby clamping the latter in a predetermined position and limiting the opening movement thereof.

Further objects of the invention are to form 30 said pintle adjustable longitudinally so as to regulate the clearance between the enlargement thereof and the removable hinge member, thereby controlling the extent of swinging movement of the latter.

Additional objects of the invention are to provide a hinge of simple and efficient construction wherein the pintle member is operable in axial direction by the movable member of the hinge to limit the opening movement of the closure member and to provide simple means for regulating the extent of the opening movement of said closure member.

With these and other objects in view, my

invention consists in certain novel features of construction and arrangement of parts, hereinafter more fully described and claimed, and illustrated in the accompanying drawings, in which—

Figure 1 is a front elevational view of my improved hinge.

Figure 2 is a top plan view of same.

Figure 3 is an enlarged cross section showing the closure member in closed position.

Figure 4 is a similar view but showing the movable hinge member in open locked position.

Figure 5 shows a modified form of my invention.

Figure 6 shows still another modified form of my invention.

Figure 7 shows still another modified form of my invention.

Briefly stated, my invention consists in forming the pintle member of the hinge movable in axial direction during the swinging movement of the closure member, whereby the movable hinge member can be clamped between said pintle member and the stationary hinge member when said closure member is opened to a predetermined position. The pintle member is adjustable longitudinally so as to increase or decrease the axial movement thereof and increase or decrease the extent of the opening movement of the closure member correspondingly.

To accomplish this purpose, the pintle element has a screw-threaded engagement with the knuckle of one of the hinge elements and one of said elements is rotatable relatively to the other to cause the axial movement of the pintle.

Referring by numerals to the accompanying drawings, which illustrate a practical embodiment of my invention, 10 indicates a stationary hinge member which is secured to a frame 11, and 12 is the movable hinge member which is secured to a closure member 14. As shown in the preferred form 90 (Figures 1 to 4) member 10 has a knuckle 10^a which is provided with a threaded bore 15 and movable hinge member 12 has a knuckle 12^a which is provided with a smooth bore 16.

Extending through these bores, which are coaxially arranged, is a pintle member or pin 17 provided at its upper end with a head 18. This pin 17 has its lower half provided with a screw-thread, as at 17^a, for engagement with the threaded bore 15 of member 10. The upper half of this pin is smooth and fits loosely in the bore 16 of member 12. Pin 17 can be adjusted in bore 15 so as to provide sufficient clearance between head 18 and the upper end of knuckle 12^a of member 12, as shown in Figure 3.

Pin 17 is held in non-rotative engagement with member 12 in any suitable manner, preferably by means of a locking member 19 which is pivotally mounted at one end to hinge member 12 as indicated at 20 and is movable downwardly so as to bring the free end thereof, which terminates in a downwardly presented cap 21, over the head 18. Head 18 is formed non-circular, preferably being hexagonal, and the recess formed in cap 21 is similarly formed so that said cap fits snugly over said head and holds pin 17 against rotation. Thus with member 19 in engagement with pin 17 the latter is caused to rotate partially when the closure member is moved in open position. This partial movement of pin 17 causes the latter, by virtue of its screw-threaded engagement with bore 15, to move downwardly until the head 18 presses against the upper end of knuckle 12^a and clamps the latter between said head 18 and the upper end of knuckle 10^a, thereby locking the closure member against further opening movement.

When the closure member is moved in the opposite or closing direction, pin 17 is partially rotated correspondingly, causing the head 18 thereof to move upwardly away from the upper end of knuckle 12^a.

Thus it will be seen that the extent of the opening movement of the closure member is controlled by the clearance existing between the upper end of knuckle 12^a and head 18. This clearance can be regulated by lifting member 19 out of engagement with head 18 and partially turning pin 17 by means of said head in the proper direction, either to increase or decrease the clearance between said head and knuckle 12^a, whereupon member 19 is dropped into engagement with said head so as to lock said pin in non-rotative engagement with the swingable hinge member 12.

In the modified form shown in Figure 5, a pin 24 is shown having its head 25 provided with a vertically disposed aperture 26 adapted to receive a pin 27. The lower end of this pin is adapted to be seated in an upwardly presented recess 28 formed in the open end of the movable knuckle 29.

There is a number of recesses 28 arranged in spaced relation about the axis of pin 24 and the operating clearance of the pin can

be regulated by adjusting said pin or pintle 24 and bringing the locking pin 27 in the appropriate recess 28.

The modified form shown in Figure 6 shows a stationary leaf knuckle 30 having a non-circular bore 31 and a knuckle 32 of the movable leaf member having a threaded bore 33. A pintle pin 34 has its upper half threaded for engagement with threaded bore 33 and has its lower half formed non-circular in cross section for engagement with bore 31. The lower end of pin 34 has a threaded extension 35 on which is screw-seated a nut 36. Normally, or when the closure member occupies closed position, this nut 36 is spaced the appropriate distance from the lower end of knuckle 30. When the closure member is actuated the threaded bore 33 of knuckle 32 through its engagement with the threaded portion of the pintle causes upward movement thereof, thereby bringing nut 36 against the lower end of the stationary knuckle 30 and limiting the opening movement of the movable knuckle 32. Nut 36 can be adjusted to regulate the longitudinal movement of pintle 34. As pin 34 has non-rotative engagement with the stationary knuckle 30 it is held against rotative movement and is moved upwardly by the opening movement of the movable knuckle 32, thus bringing the nut 36 against the stationary knuckle and causing the movable knuckle 32 to be drawn against the upper end of the stationary knuckle.

In the modified form shown in Figure 7 the bolt 37 is locked to the hinge member 12 through the mechanism of a cap 38 which fits over the head 39 of said bolt. The interior of this cap is non-circular in cross section to conform to the conformation of said nut and the upper end 40 of the knuckle 12^b, which upper end 40 is of the same contour as said nut. The cap 38 fits closely over head 39 and end 40 and locks said head against rotation. The cap is held in position on the head by a screw 41 which is screw-seated in the threaded opening formed in said head and has its upper end bearing on said cap. This construction eliminates the use of pivoted caps or locking members and presents a neat appearance.

My improved hinge effectively limits the swinging movement of the closure member and also serves as a check, as the clamping or pressure against the movable hinge member is increased gradually. The device provides a neat appearance, is inexpensive to manufacture, and is simple to install and operate.

While I have shown the preferred embodiments of my invention, it is obvious that various other changes in the construction and arrangement of parts can be made and substituted for those herein shown without departing from the spirit of my invention.

I claim:

1. A self-locking hinge comprising a sta-

130

tionary hinge member, a movable hinge member, a pintle member having a screw-threaded engagement with one of said hinge members and a loose engagement with the other 5 hinge member, and means for effecting non-rotative engagement between said pintle and said last-mentioned hinge member whereby the actuation of the movable hinge member causes displacement of said pintle in axial 10 direction and clamps said movable hinge member against said stationary hinge member during the opening movement of said movable hinge member.

2. A hinge for swinging closures comprising 15 a stationary hinge member, a movable hinge member, a pintle extending through the knuckles of said hinge members for holding the latter in coaxial assembled relation, said pintle having a threaded engagement 20 with the knuckle of said hinge member and being loosely and non-rotatably mounted in the knuckle of the other hinge member for movement in axial direction whereby the swinging movement of the movable hinge 25 member causes longitudinal displacement of said pintle and clamps said movable hinge member against said stationary hinge member.

3. A hinge for swinging closures comprising 30 in combination, a stationary hinge member; a movable hinge member, a pintle therefor having a threaded engagement with one of said hinge members and being loosely mounted in the other hinge member for 35 movement in axial direction, and means for locking said pintle against rotative movement relatively to the hinge member in which it is loosely mounted, said means being adapted to permit longitudinal movement of said 40 pintle relatively to said hinge member.

In testimony whereof I hereunto affix my signature this 5th day of September, 1929.

GEORGE H. CHESTER.
